REVOLVING DOOR AND CABINET

William J. Kurstin and Vito M. Renna, Los Angeles, Calif.; said Kurstin assignor to said Renna

Application July 24, 1947, Serial No. 763,178

8 Claims. (Cl. 312—292)

1

This invention relates to new and useful improvements in building construction and more particularly to a revolving door and cabinet or closet construction, the primary object of the invention being to provide a combination cabinet, closet, or the like, and revolving door which will save space, provide greater shelf space, allow for greater hanging space, permit greater and more simple accessibility to the contents of the cabinet or closet and permit said contents to be readily aired and sprayed when desired.

A further object of the invention resides in providing a device of the character mentioned which may be readily and quickly installed in new buildings or installed in old structures with slight alteration of closet space.

Still another object of the invention resides in providing a structure of the character mentioned which is simple and durable in construction, comparatively inexpensive to manufacture and one which will be very efficient and useful in operation.

With these and numerous other objects in view, our invention consists of the novel features of construction, combination and arrangement of parts as will be hereinafter referred to and more particularly pointed out in the specification and claims.

In the drawings, forming a part of this application,

Figure 1 is a front elevational view of our improved door and cabinet construction as applied to a structure, the latter being broken away,

Figure 2 is a vertical section therethrough, as seen on the line 2—2 of Figure 1,

Figure 3 is a horizontal section through the structure as seen on the line 3—3 of Figure 1,

Figure 4 is a front elevation, showing the door revolved to a position diametrically opposite that shown in Figure 1,

Figure 5 is an enlarged front elevation, showing the door partially revolved,

Figure 6 is a vertical sectional view, as seen on the line 6—6 of Figure 5, showing the upper swivel construction, and

Figure 7 is a similar view, as seen on the line 7—7 of Figure 5, showing the ball-bearing lower swivel connection with the door.

In small apartments, the usual complaint is lack of closet or cabinet space. When there are sufficient closets or cabinets, same are usually inadequate in space and otherwise improperly designed. They are dark, lack shelf space and do not permit of ready access to the contents, either for removal or for airing and spraying.

2

Even when a closet is spacious, such as may be provided in homes or large apartments, ready access to the contents for airing and spraying thereof is usually not possible. It is the purpose of our invention to overcome these difficulties by the provision of a combination revolving door and cabinet or closet, which may be initially provided when the apartment or home is constructed or which may be installed with slight alteration to a closet or cabinet already in existence.

In describing the invention, we shall refer to the drawings in which similar reference characters designate corresponding parts throughout the several views and in which the numeral 1 designates the wall of a structure in which there is formed a cavity 2 constituting a closet or cabinet. Surrounding the opening forming this cavity 2 and secured in any desired fashion to the wall 1 is the doorway frame 3. Mounted in the corners of the cavity 2 in vertically spaced relation are the shelf-like members 4, which may be made of wood, plastic, metal or any other desired material and the inner opposed edges of said shelf members are arcuately designed as shown at 5, for a purpose to be hereinafter and more particularly set forth. Whereas, we have shown in the drawings four such shelves in each corner of the closet or cavity, one spaced above the other, it will be understood that a lesser or greater number may be provided, as desired. These shelves, obviously, permit of the storage thereon of any desired articles which a housewife may wish to keep concealed, but readily accessible.

An essential feature of our invention is the closure for this closet or cavity, which will provide a function other than a mere closure. To this end, we provide a door or closure 6, the frame of which is divided into three panels 7, 8 and 9. The outer panels 7 and 9 are flat panels of wood, plastic, metal or any other desired material, the intermediate panel 8 having a mirror applied to the outer face thereof. This intermediate panel 8 with the mirrored outer face is formed into a hinged closure which opens into a closet or compartment 10 formed on the rear face of the closure or door 6 by a semi-cylindrical wall 11, the edges of the latter being mounted in strips 12 on the rear face of said closure, as best illustrated in Figure 3 of the drawings. This semi-cylindrical wall 11 has a top 13 and a bottom 14 and secured to said wall 11 in spaced relation between the top and bottom 13 and 14 are the shelves 15. Thus, it will be

seen that the closure 6 for the cavity or closet 2 is provided in itself with an additional compartment which is particularly useful in supporting and concealing linens, bed coverings and the like.

Supported on the peripheral face of the semi-cylindrical wall 11 adjacent the upper end thereof and projecting radially outwardly from said wall is the semi-circular shelf 16, upon which may be supported hats, or other articles. A semi-circular rod 17 having its ends mounted in the cross-bars 18 secured on the rear face of the closure 6 provides an arcuate rack for hanging of clothes thereon. This bar or rack 17 is spaced radially outward from the wall 11 to permit the freedom of the hanging of clothes on said rack.

Secured to the panels 7 and 9 adjacent the lower ends thereof are the ends of a semi-circular rod 19 and slightly below this rod 19 supported on the bottom 14 is a semi-circular shelf 20. This rack or bar 19 and the lower shelf 20 constitute a shoe rack for the storage of numerous pairs of shoes.

The closure 6 is adapted to be revolvably mounted in the door frame 3. In carrying out this idea, we provide a ball-bearing structure 21 between the lower end of the closure 6 and the base of the frame of the cavity, as shown in Figure 7, and the closure 6 is provided at its upper end centrally with a swivel pintle 22 fitting in a socket 23 in the frame 3. This constitutes a most simple swivel and ball-bearing structure to permit of the closure 6 being readily revolved in the door frame, but it will be understood that any other form of swivel and ball-bearing construction may be utilized, as desired.

Thus it will be seen that when the closure 6 is positioned as shown in Figure 1, articles of wearing apparel, linens, and various other articles may be concealed within the cavity or closet space. The mirror in the central panel of the closure will serve its usual useful function and without revolving the closure, access may be readily had to linens and other articles which may be stored in the closet space or compartment 10 provided in the closure 6. The mirrored closure or panel 8 may be readily opened by pulling on the handle 24. Access to the cavity or closet 2 may be had by partially revolving the closure 6 and to facilitate the movement by pulling, we provide the handles 25 on this closure. It is apparent through the revolving of the closure to a position as shown in Figure 4 that ready access may be had to the articles that may be supported on the rear face of said closure, whether same are hanging from the rack 17, supported on the shoe rack 19, or carried on the shelf 16. By partially revolving the closure 6 to a position as shown in Figure 5, it will be seen that entry to the cavity 2 may be had to either remove articles from the shelves 4 or for dressing room purposes, the mirror on the central panel being useful in this connection.

The designing of the shelves 4 with arcuate edges 5, as aforesaid, permits of the door or closure 6 to be readily revolved without contact with the said shelves and said shelves so designed constitute ways between which the door may readily revolve.

The described construction is characterized both by advantageous configuration of the enclosed spaces and by full use of the available space. With respect to advantageous configuration, it is to be noted that the space in which

clothes are suspended from the rack 17 (see Figure 3) is of annular configuration and is uniform in width or radial dimension. This arrangement permits the clothes to hang in series with full width for each garment. The garments most often needed may be placed next to the door at both ends of the arcuate rack 17. It will be noted that when clothes are arranged in this manner a space is left near the axis of curvature of the arcuate rack 17 but this space is occupied by the compartment 15. To make this relationship possible, the compartment 15 must be located near the axis of rotation of the door and the lateral extent or dimension of the central compartment measured radially must be substantially less than the width of the door. When the central compartment is so located and so dimensioned, it provides the desired space for the hung garments which space extends radially outward from the inner compartment towards the circle defined by the swinging movement of a vertical edge of the door. This outer circle is shown in broken lines in Figure 3.

We have shown and described this construction as particularly applicable to a wall of a structure, but it will be readily understood that this construction may be applicable to a cabinet separate from a wall structure and to this extent we do not wish to be limited to installation to homes or apartments, since a cabinet of this construction may be readily built and sold to the public as a unit for use anywhere.

From the foregoing description of the construction of our improved revolving door and cabinet or closet structure, the method of construction and application to use will be readily understood and it will be seen that we have provided a comparatively simple, inexpensive and efficient means for carrying out the various objects of the invention. While we have particularly described the elements best adapted to perform the functions set forth, it is apparent that various changes in form, proportion and in the minor details of construction may be resorted to without departing from the spirit or sacrificing any of the principles of the invention.

Having thus described our invention, what we claim is:

1. In a closet or cabinet construction, walls forming a cavity with an opening at the front, a door for said opening mounted for rotation about an upright axis, a compartment mounted on the inner side of said door in the region of said axis with an opening in the door for access to the compartment, the lateral extent of said compartment measured radially of said axis being substantially less than the same measurement of the door to provide back of the door a space extending radially from the compartment to the circle defined by the swinging side edge of the door, said space being of sufficient radial dimension to accommodate a hung garment, and structure supported by said door in the upper region of said space to suspend garments in said space.

2. In a closet or cabinet construction, walls forming a cavity with an opening at the front, a door for said opening mounted for rotation about an upright axis, a compartment mounted on the inner side of said door in the region of said axis with an opening in the door for access to the compartment, the lateral extent of said compartment measured radially of said axis being substantially less than the same measurement of the door to provide back of the door a space extending radi-

ally from the compartment to the circle defined by the swinging side edge of the door, said space being of sufficient radial dimension to accommodate a hung garment, and a shelf supported by said door in the upper region of said space.

3. In a closet or cabinet construction a combination as set forth in claim 1 in which said structure to suspend garments comprises an elongated member curved substantially concentric to said axis and adapted to carry conventional clothes hangers. 10

4. In a closet or cabinet construction, walls forming a cavity with an opening at the front, a door for said opening mounted for rotation about an upright axis, a compartment mounted on the inner side of said door in the region of said axis with an opening in the door for access to the compartment, the lateral extent of said compartment measured radially of said axis being substantially less than the same measurement of the door to provide back of the door a space extending radially from the compartment to the circle defined by the swinging side edge of the door, and structure supported by said door to store articles in said space. 15

5. In a closet or cabinet construction, walls forming a cavity with an opening at the front, a door for said opening mounted for rotation about an upright axis, a compartment mounted on the inner side of said door in the region of said axis with an opening in the door for access to the compartment, the lateral extent of said compartment measured radially of said axis being substantially less than the same measurement of the door to provide back of the door a space extending radially from the compartment to the circle defined by the swinging side edge of the door, said space being of sufficient radial dimension to accommodate a hung garment, a structure supported by said door in the upper region of said space to 40 suspend garments in said space, and a shelf supported by said door in the lower region of said space.

6. In a closet or cabinet construction, walls forming a cavity with an opening at the front, a door for said opening mounted for rotation about an upright axis, means including an upright arcuate wall mounted on the inner side of said door forming an inner compartment, said door having an opening for access to the compartment, the lateral extent of said compartment measured radially of said axis being substantially less than the same measurement of the door to provide back of the door a space extending radially from the compartment to the circle defined by the swinging side edge of the door, said space being of sufficient radial dimension to accommodate a hung garment, and structure supported by said

door in the upper region of said space to suspend garments in said space.

7. In a closet or cabinet construction, walls forming a cavity with an opening at the front, a door for said opening mounted for rotation about an upright axis, a compartment mounted on the inner side of said door in the region of said axis with an opening in the door for access to the compartment, said compartment extending upward from a level near the lower edge of said door to a level near the upper edge of the door, the lateral extent of said compartment measured radially of said axis being substantially less than the same measurement of the door to provide back of the door a space extending radially from the compartment to the circle defined by the swinging edge of the door, said space being of sufficient radial dimension to accommodate a hung garment, and a closure for said compartment mounted on said door. 20

8. In a closet or cabinet construction, a wall having a depression forming a cavity therein, a frame for said cavity, shelves mounted in the corners of said cavity distant from the opening leading to said cavity, a door for said cavity revolvably mounted at the top and bottom thereof in the frame of said cavity, a panel hinged to said door to form an auxiliary closure, an arcuate wall mounted on the rear face of said door and forming with said auxiliary closure an intermediate closet, shelves mounted on said arcuate wall to support articles within said intermediate closet, additional shelves mounted on the rear face of said door and partially surrounding said arcuate wall for support of further articles thereon, and a rack mounted on the rear face of said door partially surrounding said arcuate wall for the support of additional articles. 25
